UNITED STATES PATENT OFFICE.

WILLIAM F. CAVANAGH, OF BROOKLYN, NEW YORK, ASSIGNOR TO ROBERT GAIR COMPANY, OF BROOKLYN, NEW YORK, A CORPORATION OF NEW YORK.

SLIDE-LOCK SUPPORT.

Application filed July 26, 1920. Serial No. 398,915.

To all whom it may concern:

Be it known that I, WILLIAM F. CAVANAGH, a citizen of the United States, residing in Brooklyn, in the county of Kings and State of New York, have invented certain new and useful Improvements in Slide-Lock Supports, of which the following is a specification.

My present invention relates to an improvement in counter cartons for receiving, shipping and displaying goods therein.

One object of my invention is to provide a counter carton of the class described formed from a single blank and without the use of glued-up joints or connections.

Another object of my invention is to provide a counter carton of the class described provided with a rest or easel-back for supporting the carton in position for display of the contents.

A principal feature of my invention is the employment of a double bottom, outer and inner, for the receptacle portion of the carton, the outer bottom having a slidably movable portion arranged to provide the rest or easel-back, the cover of the carton, when the rest or easel-back is in operation, standing in a position for displaying printed or other matter contained thereon.

Another feature of my invention, is the employment of a double bottom, (outer and inner) double sides, (outer and inner) tensioning means for retaining the outer and inner sides and the ends in operable relation at one side of the receptacle portion of the carton, and locking means for retaining the outer and inner sides and the ends in operable relation at the other side of the receptacle portion, the tensioning means, inner bottom and one of the inner sides being consecutively foldably connected and co-operating with the locking means for retaining the receptacle portion in operative assembled form.

These and other capabilities of the invention will be disclosed in the course of the description thereof.

In the accompanying drawings which form part of this specification,

Figure 1 is a perspective view of the carton in folded assembled form.

Fig. 2, is a cross-sectional view on the central transverse line of the carton with the rest or easel-back in operative position for supporting the carton.

Fig. 3, is a perspective view of the carton, bottom up, and showing the rest or easel-back in raised position, and the adjacent portion of the outer bottom from which the rest or easel-back is cut out and with which it cooperates.

Fig. 4, is a view on an enlarged scale, of the blank from which the carton is formed.

Fig. 5, is a view of the blank, on the same scale as Fig. 4, in partially folded form.

Similar letters or numerals refer to similar parts throughout the several views.

Reference being had to Fig. 5, the carton, which preferably is formed from a single sheet of cardboard or other suitable material, consists of a rectangular main portion A comprising an outer bottom portion 10, a free-hanging outer side-forming element or member 11, an outer side-forming element or member 12, a tension element or member 13, an inner bottom portion 14, an inner side-forming element or member 15, a cover portion 16, and a flap element or member 17 for the cover portion.

The main portion A is provided at its upper end with lateral extensions B and C, these extensions comprising end-forming elements or members 18 and 19, a free-hanging two-part inner side-forming element or member 20-20', and free-hanging locking-tabs 21 and 22.

The outer bottom portion 10 is in length the desired length of the carton or container and in width is the desired width thereof; the term length being used with reference to the longitudinal line of the outer bottom portion and not the longitudinal line of the main portion A.

The outer bottom 10 is foldably connected along its upper line to the free-hanging outer side-forming element or member 11, and along its lower line to the outer side-forming element or member 12, and along its respective ends to the end-forming elements or members 18 and 19.

The free-hanging outer side-forming element or member 11 is in length the length of the outer bottom portion 10 and in width is the desired depth of the carton or container.

The outer side-forming element or member 12 is foldably connected along its lower line to the tensioning element or member 13 and in length and width is the same as the free-hanging outer side-forming element or member 11.

The tensioning element or member 13 is foldably connected along its lower side to the inner bottom 14, and the length and width of inner bottom 14 are substantially the same as the outer side-forming element or member 12.

The inner bottom 14 is foldably connected along its lower line to the outer side-forming element or member 15, and in length and width is the same as the outer bottom 10.

The inner side-forming element or member 15 is foldably connected along its lower line to the cover portion 16 and in length and width is the same as the outer side-forming element 11.

The cover portion 16 is foldably connected along its lower line to the flap element or member 17 and in length and width is the same as the outer and inner bottoms 10 and 14.

The flap element or member 17 in length is the same as the cover portion 16 and in width is suitable for tucking into the receptacle portion of the carton.

The lateral extensions 21 and 22 in width are the width of the outer side-forming element or member 11, and in length respectively comprise the locking tabs 21 and 22, the end-forming elements or members 18 and 19, and the free-hanging two-part inner side-forming element or member 20-20', and extend downwardly along each side of the main portion A from a point somewhat above the upper line of the outer side-forming element or member 11 to a point slightly below the tensioning element or member 13.

The end-forming elements or members 18 and 19 are each in length the width of the outer bottom portion 10, and in width are the same as the outer side-forming member or element 11.

Each part of the free-hanging inner side-forming element or member 20-20' is in width the same as the end-forming elements or members 18 and 19, and in length each is somewhat more than one-half the length of the outer bottom 10, the intention being that the length of each of the parts 20-20' should be such as to render these parts capable of being brought into overlapping relation to form when overlapped an inner side for the receptacle portion of the carton. The parts 20-20' are respectively foldably connected at their upper ends to the lower ends of the end-forming elements or members 18 and 19.

The locking-tabs 21 and 22 are respectively foldably connected at their ends to the end-forming elements or members 18 and 19, and are provided at their upper ends with interlockable head-notches 23 and 24. Each locking-tab is in length, exclusive of its head-notch, substantially one-half the length of the outer side-forming element

or member 11, and in width is the same as the adjoining end-forming element or member.

The outer bottom portion 10 is provided along its upper line with an easel-back element or member 25 cut therefrom, foldably connected thereto and free-hanging, and provided with a slide-lock extension 26, the element or member 25 preferably being square and having sides each preferably substantially one-third the length of the outer bottom portion 10. The easel-back element or member 25 is foldable on its middle horizontal line 25'. The slide-lock element or member 26 extends at each of its ends beyond the points of intersection therewith of the sides of the easel-back element or member 25, the ends 27-27' of the slide-lock preferably being rounded or otherwise suitable for the purpose later described. An open space 28, Fig. 3, which in all respects conforms to the shape of the easel-back element or member 25 and slide-lock 26 is thus formed in the outer bottom portion 10, this space having in the sides thereof near the lower ends of the sides downwardly extending slits or cuts 29-29', Figs. 3 and 5, the purpose of which is later described.

To fold the carton or container into operative assembled form, again referring to Fig. 5, and the carton lying before the operator as shown in Fig. 5, the free-hanging outer side-forming element or member 11, and the end-forming elements or members 18 and 19 are folded upwardly to substantially vertical positions on the lines of connection to the outer bottom portion 10, and the locking tabs 21 and 22 are folded inwardly on the lines of connection to the end-forming elements or members 18 and 19, and interlocked outwardly or rearwardly of the element or member 11 by means of the head-notches 23 and 24 thus locking the end-forming elements or members 18 and 19 and the free-hanging outer side-forming element or member 11 in operative folded relation at one side of the carton, the head-notches being interlocked inwardly relative to each other, as shown in Fig. 1 to protect the head-notches. The parts of the free-hanging two-part inner side-forming element or member 20-20' are folded inwardly on the lines of connection to the end-forming elements or members 18 and 19 and into overlapping relation. The outer side-forming element or member 12 is folded upwardly along the line of connection to the outer bottom portion 10 and parallel to and into contact with the two-part inner side-forming member or element 20-20'; the tensioning element or member 13 is folded downwardly on the line of connection to the outer side-forming element or member 12 and carried over the outer side-forming and overlapping inner side-forming elements or members, and en-

gaging at its ends the inner faces of the end-forming elements or members 18 and 19, and retaining the two-part inner side-forming and the outer side-forming elements or members 20-20' and 12, and the end-forming members 18 and 19 in operative folded form at this side of the carton. The inner bottom 14 is pressed down into contact with the outer bottom 10, and the inner side-forming element or member 15 is folded upwardly on its line of connection to the inner bottom 14 and brought into contact with the outer side-forming element or member 11, the receptacle portion of the carton or container thus being in complete operative folded form. The cover portion 16 is folded upwardly, on the line of connection to the inner side-forming element or member 15, and drawn forwardly or towards the operator and over the receptacle portion, the flap portion 17 being inserted or tucked into the receptacle portion into engagement with the inner face of the tensioning element or member 13, being held by the tension or flexibility of the cover.

To form the easel-back or rest the portion 25 is folded upwardly on its central line 25', and the ends 27-27' of the slide-lock 26 being turned slightly downward so that in withdrawing, due to the upward folding movement of the portion 25, from the conforming space or opening 28, Figs. 3 and 5, they will slide between the outer and inner bottoms 10 and 14, these bottoms thus providing a slideway for the ends 27-27'.

The ends 27-27' are drawn further upwardly so that the lower edges of the ends are above the upper line of the slits or cuts 29-29'; the portions of the outer bottom 10 immediately adjacent to the slits or cuts, below the slits or cuts, are bent slightly inwardly to provide stops or detents 30-30', with which the ends 27-27' by downward pressure on the easel portion 25 are brought into engagement, the weight of the carton or container retaining the slide-lock in this position and preventing collapse of the easel-back when the carton or container is supported in display position thereby. To collapse the easel-back or rest 25 it is drawn upwardly on the fold 25' so that the ends 27-27' are out of engagement with the slits or cuts 29-29' and the stops or detents 30-30' are bent upwardly to their former or normal position to avoid interference with the sliding movement of the slide-lock ends 27-27'. The portion 25 is then pressed downwardly on the fold 25', the ends 27-27' of the slide-lock sliding between the outer and inner covers and again into conforming relation with the space or opening 28 in the outer bottom 10.

Referring to Fig. 4, which shows the blank from which the carton is formed, the dotted lines denote scoring and the solid

lines within the confines of Fig. 4 denote cuts for folding the blank on the lines thereof.

The blank which is a single sheet of cardboard or other suitable material, consists of a main portion A, oblong in shape and in width the desired length of the carton or container, and extensions B and C which in width are the desired depth of the carton, and which extend downwardly along the sides of the portion A from a point somewhat above the upper line thereof to a point slightly below the middle transverse line thereof.

The main portion A comprises the free-hanging outer side-forming section 11, the outer bottom section 10, the outer side-forming section 12, the tensioning section 13, the inner bottom section 14, the inner side-forming section 15, the cover section 16 and the flap section 17, the lengths of all these sections being the same; the width of the outer bottom 10, inner bottom 14, and cover section 16 being the same; the width of the outer side-forming section 12, tensioning section 13, and inner side-forming section 15 being the same and the same as the width of the side-forming section 11, and the width of the flap section 17 being suitable for tucking in purposes.

The lateral extensions B and C comprise the two-part free hanging inner side-forming sections 20 and 20', the end-forming sections 18 and 19, and the locking-tab sections 21 and 22, provided with the head notches 23 and 24.

The easel-back section 25 comprises the side-lock extension 26 having the ends 27 and 27' for sliding engagement between the outer and inner bottoms and engagement with the stop means, or slits, 29 and 29' in the outer bottom 10.

Having thus described my invention, it should be understood that there may be modifications thereof and variations therein without departing from the spirit of the invention or exceeding the scope of the appended claims.

Having thus described my invention, I claim:

1. A container formed by folding comprising, a goods-receptacle portion having an inner bottom and an outer bottom, the outer bottom having a cut out portion, an easel-back normally positioned in the cut out portion of the outer bottom and connected at one of its ends to the outer bottom and positionable for providing a rest for the goods-receptacle portion in display position, the outer bottom being provided with stop means appurtenant to opposite edges of the outer bottom, said edges being formed by the cut out portion, and means at the free end of the easel-back slidable between said outer and inner bottoms and engageable with said

stop means for maintaining the easel back in supporting position.

2. A container formed by folding comprising, a goods-receptacle portion having an outer bottom and an inner bottom, the outer bottom having a cut out portion, an easel-back normally positioned in the cut out portion of the outer bottom and connected at one of its ends to the outer bottom and positionable for providing a rest for the goods-receptacle portion in display position, the outer bottom being provided with stop means arranged laterally relative to opposite edges of the outer bottom, said edges being formed by the cut out portion, and means at the free end of the easel back slidable between said outer and inner bottoms and engageable with said stop means for maintaining the easel-back in supporting position.

3. A container formed by folding comprising, a goods-receptacle portion having an outer bottom and an inner bottom, an easel-back cut from said outer bottom and foldably connected at one of its ends thereto and foldably positionable for providing a rest for the goods-receptacle portion in display position, the outer bottom being provided with slits in opposite edges thereof, said edges being formed by the cut-out portion of the outer bottom, the easel back having ends extending beyond the side lines of the easel-back slidable between the outer and inner bottoms and engageable with said slits.

4. A container formed by folding having a goods-receptacle portion comprising an outer bottom and an inner bottom, the outer bottom having an easel-back connected thereto and being provided with stop means, the easel-back being positionable as a supporting rest on the under side of the outer bottom and being provided with a slide-lock slidable between the outer and inner bottoms and engageable with said stop means of the outer bottom for maintaining the easel-back in supporting position.

5. A blank provided with scoring and cuts for forming a container by folding the blank on the scoring and cuts, said blank being of suitable material and comprising an outer bottom section and an inner bottom section, the outer bottom section comprising an easel-back portion formed by parallel cuts and a slide-lock portion formed by a cut extending transversely to the parallel cuts and providing ends for the slide-lock slidable between the outer and inner bottoms, the outer bottom having slits therein intersecting said parallel cuts for engagement of said ends of the slide-lock therewith.

6. In a display box, an inner and an outer bottom panel, an easel for supporting the box in inclined position, cut from the outer bottom panel, but integral therewith at one end, transversely folded and the free end thereof being interlocked with the edge portions of the opening from which it was cut.

WILLIAM F. CAVANAGH.
